UNITED STATES PATENT OFFICE

2,349,126

THERMOSTATIC ELEMENT

David W. Abernathy, Chicago, Ill., assignor to
Products Development, Inc., Chicago, Ill., a
corporation of Illinois

Application June 9, 1942, Serial No. 446,332

3 Claims. (Cl. 200—138)

This invention relates generally to thermostatic elements and more particularly to a novel and improved element to be used in connection with the heating elements used to heat wound tresses of hair as for the permanent waving thereof.

The primary object of the invention is to provide a novel and improved thermostatic element.

A further object of the invention is to provide a novel thermostatic element which is simple and compact and in which the bi-metal element is not subject to undue stress at low temperatures.

A further object of the invention is to provide a novel and improved thermostatic element which will respond accurately to high temperatures for which it has been adjusted.

A further object of the invention is to provide a novel thermostatic element which may be easily associated with the shell of a heater clamp so that same is responsive to the heat immediately.

A still further object of the invention is to provide a novel heater clamp having a thermostatic element associated therewith.

Other objects of the invention lie in the specific constructional details of the thermostatic element and the heater clamp.

With the foregoing and other objects in view which will appear as the description proceeds, the invention consists of certain novel features of construction, arrangement and combination of parts hereinafter fully described, illustrated in the accompanying drawing, and particularly pointed out in the appended claims, it being understood that various changes in the form, proportion, size and minor details of the structure may be made without departing from the spirit or sacrificing any of the advantages of the invention.

For the purpose of facilitating an understanding of my invention, I have illustrated in the accompanying drawing a preferred embodiment thereof, from an inspection of which, when considered in connection with the following description, my invention, its mode of construction, assembly and operation, and many of its advantages should be readily understood and appreciated.

Referring to the drawing in which the same characters of reference are employed to indicate corresponding or similar parts throughout the several figures of the drawing:

Fig. 1 is a perspective view of a heater clamp such as used in heating wound tresses of hair

in the permanent waving thereof, having my invention incorporated therein.

Fig. 2 is a perspective view of one of the jaws of the clamp broken away in order to show the inner construction thereof.

Fig. 3 is a sectional view taken through a clamp member taken generally along the line 3—3 of Fig. 1.

Fig. 4 is a side elevational view of the thermostatic element.

Fig. 5 is a perspective view of the element prior to being installed into the shell of the clamp jaw.

In the permanent waving of hair by means of electrical heaters, it has been customary to utilize thermostats for the purpose of maintaining the temperature of the heaters substantially constant. This is desirable for reasons of control and uniformity. In the manufacture of the heating clamps the thermostatic element is associated with said clamps and is adjusted to open the circuit to the heating elements when a certain predetermined temperature theoretically exists at the clamp jaw. The types of thermostatic elements heretofore used have been constructed in such manners that the bi-metallic element, referred to sometimes as the bi-metal, is subject to undue stress at the early part of its life and hence its characteristics are not as contemplated. It is hence necessary to replace the thermostats or readjust them often, or provide compensation for the change of characteristics in some other manner. Either excess heat or fluttering may result from misadjusted thermostatic elements.

Probably the greatest cause for the strain occurring is that reverse stress is placed upon the bi-metal when same is subject to low temperatures, as for example when transported in cold weather or stored in unheated warehouses. Even if the thermostatic element is subject to ordinary temperatures different from those under which it will operate, and maintained that way for a long while, its characteristics may change perceptibly.

My new invention besides eliminating the disadvantages above described is so small and compact that instead of being associated with the heater clamps as has heretofore been customary, it may be associated with jaws of the clamps at a point immediately adjacent the heating element and hence may more accurately respond to the proper temperature and does not depend for its operational heat upon that portion of the heat from the element which is conducted to it along

the shell as has been the case of prior thermostatic elements.

Referring now to the specific details of the invention, the reference character 10 designates generally a clamp of the type used in giving the so-called "machine" permanent wave. The clamp 10 comprises a pair of clamp arms 11 terminating in jaws 12 which have the inner surfaces 13 thereof concave in order to hold and heat therebetween a tress of hair which has been suitably wound or formed to some desired configuration. Electrical wires 14 supply current to a heating element which has been generally shown as a mica member 15 wound with resistance wires 16, embedded in a ceramic material or the like 17 and the whole being retained by a covering member 18. The outer portion of the jaws 12 comprises a metal shell 19 which may have its edges engaged over the covering member as shown at 20.

That portion of the clamp 10 above described is generally well known and per se is not a portion of my invention. However, the combination thereof with matter to be described is an important part of my invention.

The shell 19 is preferably formed of sheet metal and may be integrally formed with the arms 11. Said arms 11 are provided with ears 21 which cooperate with a pin 22 extending therethrough so that the arms 11 may pivot with respect to one another. A wire spring 23 normally urges the clamp jaws 12 into engagement with one another.

Integrally formed with the shell 19, I have provided a cavity 23 which is on the outer side of the jaw 12. The shell being formed of sheet metal, the cavity 23 is struck therein at the time of the drawing of said shell. Within this cavity 23, I have affixed my thermostatic element 24. Of course the cavity appears from the outside of the clamp member 12 as a somewhat rectangular protuberance 25 upon the outer surface of the shell 19. The thermostat is thus seen to be almost immediately next to the heating element contained in the covering member 18. Hence heat from the element will impinge directly upon the thermostatic element 24 and cause same to operate in the desired manner.

The thermostatic element comprises a substantially rectangular base member 26 adapted to snugly fit into the cavity 24. The base member has upwardly extending flanges 27 along portions of its longer edges which are adapted to engage the inner walls of the cavity 24. The base member 26 is lined with a layer of fiber insulating paper 28. At one end of the element 24 the base member 26 has a pair of integrally formed lugs 29 engage the ends 30 of a small strip 31 of resilient metal such as phosphor bronze, which strip is laid across the end of the base member 26. The central portion of the strip 31 is bent upwardly as shown at 32 and a contact point 33 is provided thereon. Obviously the mounting of the contact point is more or less resilient. It will be noted that for heat insulation I have provided a layer of asbestos paper 34 between the fiber paper layer 28 and the ends 30 of the strip 31.

The opposite end of the base member 26 is provided with a second strip 35 of resilient metal such as phosphor bronze engaged beneath bent over lugs 36 and insulated by said layer of fiber paper 28 and asbestos paper 34. This strip 35 is flat and is provided with a portion 37 extending forwardly of the element 24, bent back upon itself as at 38 to form a flat leaf spring, and terminating at 39. At the termination point 39, I have

welded the ends of a bi-metal member 40 and a long strip of resilient metal 41 which is provided on the free end thereof with a contact point 42 adapted to normally engage with the contact point 33. The ends of all three members 39, 40 and 41 are so intimately joined together by welding that they together form a block 38' which moves as a unit. The block 38' is tapped and suitably threaded for the reception of an adjusting screw 43 the bottom end of which is adapted to contact the top of the strip 35.

The spring 38 tends to serve as a pivot and its arms are so biased that they tend to close upon one another. Thus when the adjusting screw is rotated to cause the arms to open, the tension of the free end of the member 41 and the pressure between the contact points 42 and 33 is increased.

It will be noted that the terminus of the bi-metal member 40 is somewhat thicker than the body of the member 40 and hence there is a space 44 between the upper face of the bi-metal member 40 as caused by ordinary warm weather without said bi-metal engaging against the bottom face of the metal strip 41. Because of this there is obviously no stress placed in the bi-metal which would cause same to become permanently strained.

As for the reaction of the bi-metal 40 when it is subject to low temperatures, that is also permitted in order that there be no reverse stress placed upon said bi-metal. It will be noted that the bi-metal 40 is substantially "floating," that is to say, if it should tend to curl downwardly there is nothing to impede its movement. Considerable space may be provided for even sub-zero temperatures. The bi-metal thus retains its resilience throughout various temperature changes so that when it is finally used it will respond to the exact temperature for which it has been adjusted. At that temperature the bi-metal 40 moves upwardly, as viewed in Fig. 4, engages against the bottom face of the strip 41 and lifts the contact 42 from the contact 33. Inasmuch as there has been no strain placed upon the bi-metal, it is resilient to the extent where it opposes the reversing movement of the strip 41 and hence the return of contact will be gradual, eliminating flutter.

In prior thermostatic elements the bi-metal is usually in some manner connected with the contact carrying member so that where the element is subjected to low temperatures the bi-metal is considerably stressed since its motion is opposed by the fixed contact. This may result in the permanent strain above referred to. As to the reverse reaction of the element in warm weather, where the bi-metal is associated with the contact directly, a certain amount of the tension between the contacts is relieved, making for uncertain break temperatures.

The strips 31 and 35 are each provided with a wire lead 45 and 46 respectively, whereby same may be connected into the circuit of the electrical heater element in order to act as a switch for said circuit in the well known manner.

In view of the above description it should be apparent that not only have I provided a novel and ingenious thermostatic element which is not only efficient and positive in operation, but which is compact and well arranged so that same may be incorporated into a small space such as the cavity 24 of the clamp as described herein.

It is believed that my invention, its mode of construction and assembly, and many of its advantages should be readily understood from the

foregoing without further description, and it should also be manifest that while a preferred embodiment of the invention has been shown and described for illustrative purposes, the structural details are nevertheless capable of wide variation within the purview of my invention as defined in the appended claims.

What I claim and desire to secure by Letters Patent of the United States is:

1. A thermostatic switch adapted to open an electrical circuit at a predetermined temperature, comprising a base member, a resilient fixed contact supporting member attached to said base at one end thereof and having a contact provided thereon, resilient movable contact supporting means attached to the base member at the opposite end thereof and comprising a strip bent upon itself to form a substantially U-shaped spring, one end thereof being fixed to the base member, a bi-metal strip and a resilient contact carrying strip having a contact on the free end thereof for engagement with said fixed contact, the end of said bi-metal strip being connected to the second end of said spring, whereby said spring may control the pressure between the contacts.

2. A thermostatic switch adapted to open an electrical circuit at a predetermined temperature, comprising a base member, a resilient fixed contact supporting member attached to said base at one end thereof and having a contact provided thereon, resilient movable contact supporting means attached to the base member at the opposite end thereof and comprising a strip bent upon itself to form a substantially U-shaped spring, one end thereof being fixed to the base

member, a bi-metal strip and a resilient contact carrying strip having a contact on the free end thereof for engagement with said fixed contact, the end of said bi-metal strip being connected to the second end of said spring, whereby said spring may control the pressure between the contacts, the free end of said bi-metal strip being adapted to engage with a side of said resilient strip for causing disengagement between said contacts when the bi-metal member is subject to said predetermined temperature.

3. A thermostatic switch adapted to open an electrical circuit at a predetermined temperature, comprising a base member, a resilient fixed contact supporting member attached to said base at one end thereof and having a contact provided thereon, resilient movable contact supporting means attached to the base member at the opposite end thereof and comprising a strip bent upon itself to form a substantially U-shaped spring, one end thereof being fixed to the base member, a bi-metal strip and a resilient contact carrying strip having a contact on the free end thereof for engagement with said fixed contact, the end of said bi-metal strip being connected to the second end of said spring, whereby said spring may control the pressure between the contacts, the free end of said bi-metal strip being adapted to engage with a side of said resilient strip for causing disengagement between said contacts when the bi-metal member is subject to said predetermined temperature, but being normally spaced from said resilient strip and free to bend away from said strip when the temperature is low.

DAVID W. ABERNATHY.
